UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 27, 1926. Serial No. 144,509.

My invention relates to railway traffic controlling apparatus, and particularly to apparatus of the type wherein train-carried governing mechanism is controlled by current which is supplied to the track rails under safe traffic conditions in advance but not under dangerous traffic conditions in advance. More specifically, the present invention relates to the trackway portion of such apparatus.

In apparatus of the character specified, the train will receive a proceed indication when it occupies a section of track which is supplied with train governing current, and will incur an automatic application of the brakes when it enters a portion of track not supplied with such current unless the engineer takes suitable action, which action has been termed "acknowledgment".

One feature of my invention is the provision of apparatus associated with a railway switch for eliminating the necessity for acknowledgment when the switch is reversed and a train passes thereover.

I will describe one form of apparatus embodying my invention, and will then point out the novel features thereof in claims.

In the accompanying drawing, Fig. 1 is a diagrammatic view showing one form of apparatus embodying my invention. Fig. 2 is a plan view showing in more detail the structure of the switch shown in Fig. 1. Fig. 3 is an end view of the switch shown in Fig. 2.

Similar reference characters refer to similar parts in each of the views.

Referring first to Fig. 1, the reference characters 1 and 1^a designate the track rails of a railway track E which rails are provided with insulated joints 9 to form a track section A—B. The reference characters 2 and 2^a designate the track rails of a branch track F, which rails are at times connected with the rails 1 and 1^a, respectively, of the main track E by a switch C. When the switch is in the normal position, in which it is shown in the drawing, traffic approaching the switch will proceed on the main track E, but when the switch is reversed traffic approaching the switch will enter the branch track F.

Located adjacent the point B is a transformer T for supplying train governing current to the rails of the section A—B. The

secondary of this transformer is connected across the rails 1 and 1^a through a track battery D and a limiting impedance 8, while the primary of transformer T is connected with terminals X and Y of a suitable source of alternating current, the supply of this current to the transformer T being controlled by a contact 4 which is operated by a signal S for the section to the right of point B. Contact 4 is closed when signal S indicates proceed or caution, and open when the signal indicates stop; in other words, contact 4 is closed when the section to the right of point B is unoccupied but open when this section is occupied.

The switch C operates a circuit controller 5 which connects the movable rail 1^c with the main rail 1 to the left of switch C when the switch is in normal position, but which connects rails 1 and 1^a together to the left of switch C when the switch is reversed. The branch track F is provided with insulated joints 9^a at the fouling point, and is provided with two other insulated joints 9^b located on opposite sides of the frog at the point where rail 2^a crosses the rail 1. The rail 2^a is provided with a jumper 3 which is connected with the rail on opposite sides of the short insulated section provided by the joints 9^b. Rail 2^a is also connected with rail 1^a by a jumper 10.

Ordinarily the movable rail 1^c of the switch C will not be electrically connected with rail 2 when the switch is reversed, but if it is desirable to insure against such electrical connection, the movable rail 1^c may be caused to rise from the ties when the switch is reversed, and this may be effected by means of a wedge-shaped member 6 of insulating material located on one of the ties 7, as shown in Figs. 2 and 3.

As indicated hereinbefore, the apparatus shown herein is intended for co-operation with train carried governing mechanism which operates to give a proceed indication when the train occupies a section of track which is supplied with train governing current, but which operates to apply the brakes upon the cessation of such current unless the engineer acknowledges.

Assuming that switch C is in the normal position, a train moving toward the right will receive train governing current throughout section A—B provided that contact 4 is

closed. If switch C is reversed, however, a train entering section A—B will not receive a train governing current because circuit controller 5 is reversed to open the track circuit 5 and also to close the shunt across rails 1 and 1^a. The engineer must, therefore, acknowledge upon passing point A. There will be no train governing current supplied to the rails 2 and 2^a of the branch track F between switch C and the insulated joints 9^a, because rail 1 is not connected with either rail 2 or 2^a. The train will therefore not receive train governing current at any point 10 up to the insulated joints 9^a, and consequently, it will not be necessary for the engineer to acknowledge upon entering the branch track F.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of main track having rails 1 and 1^a, a branch track having rails 2 and 2^a connected at times with said rails 1 and 1^a respectively by a switch, insulated joints on opposite sides of the frog at

the point where rail 2^a crosses rail 1, a jumper in rail 2^a around said joints, and a second jumper connecting rail 1^a with the rail 2^a between said joints and said switch. 35

2. In combination, a section of main track having rails 1 and 1^a, a branch track having rails 2 and 2^a connected at times with said rails 1 and 1^a, respectively by a switch, insulated joints on opposite sides of the frog at the point where rail 2^a crosses rail 1, a jumper in rail 2^a around said joints, a second jumper connecting rail 1^a with the rail 2^a between said joints and said switch, and means for connecting rails 1 and 1^a electrically 40 when said switch is reversed. 45

3. In combination, a section of main track having rails 1 and 1^a, a branch track having rails 2 and 2^a connected at times with said rails 1 and 1^a respectively by a switch, insulated joints on opposite sides of the frog at the point where rail 2^a crosses rail 1, a jumper in rail 2^a around said joints, a second jumper connecting rail 1^a with the rail 2^a between said joints and said switch, means 50 for insulating rail 1 from rail 2 when said switch is reversed, and means for electrically connecting rails 1 and 1^a together when said switch is reversed. 55

In testimony whereof I affix my signature.

RONALD A. McCANN.
